SLATE FASTENER

Filed Sept. 20, 1926

Inventor.

Celestin Riesterer

UNITED STATES PATENT OFFICE.

CÉLESTIN RIESTERER, OF CHRISTIANSAND, NORWAY.

SLATE FASTENER.

Application filed September 20, 1926, Serial No. 136,693, and in Norway September 29, 1924.

Hitherto it has been customary to affix slate plates, shingles, and the like, as used for covering roofs and house walls, to the roof battens or wall battens by means of nails, but this means of connecting said parts with each other suffers from the drawback that removing damaged single or individual slate plates etc. is either very difficult or impossible, except that a certain number of the undamaged plates etc. be removed, too. But just this gives rise to further damages, viz of previously undamaged plates etc., chiefly because of the necessity to remove the nails.

These drawbacks are obviated in and by my present invention which relates to a connecting and disconnecting means for the battens and the individual plates etc. which now can be removed from, and attached to, the battens singly, and for this purpose I attach to every slate plate or shingle or the like a horizontal suspension member which extends over the entire breadth of the slate etc. and may be about hook-shaped in cross-section and serves for suspending the slate etc. from the respective batten. If any one of the thus suspended plates should break it can be removed quite easily at once, without any disturbance of the neighbouring plates etc., and a new plate etc. may be substituted for the damaged one also very easily practically in a moment; besides, examining a roof or a wall entirely in order to ascertain the condition of the plates etc. can be effected most conveniently in a perfectly, satisfying manner. A particular effect of the member affixed to the slate plate etc. resides therein that it increases considerably the resistibility of the plate etc. whereby this latter is by far less subject to being damaged, in consequence whereof the number of the plates etc. requiring exchange is greatly diminished and the periods of time after which the respective roof or wall requires repairing are considerably extended.

Several constructional forms of the invention are illustrated diagrammatically and by way of example on the accompanying drawing on which Figure 1 is a bottom-view of the first form thereof, Figure 2 a side-view of the middle part of the same, Figure 3 a separate view of the two hooks and their connecting ledges as pertaining to the slate-plate; Figures 4-6 are views like those of Figs. 1-3, but show a modification; Figure 7 is a per-

spective representation of fastening members corresponding to Figs. 1-3 and being drawn to an enlarged scale, Figure 8 shows a modification of these members and Figure 9 is a perspective illustration of four slate-plates with their fastening ledges and combined with fastening members of the kind shown in Fig. 7 placed on two battens and seen from the interior of the roof.

On the drawing, *b* denotes the slate-plate and *e* two iron hooks which are affixed to the plate *b* by pins *c* which are connected by a ledge *f*. In the constructional form shown in Figs. 1-3 the ledge *f* is connected with the other legs of the hooks *e*, and the pins *c* are used for its connection also. There is one pin *c* for each hook, and the hooks may be used over and over again if the plate should break. Owing to the hooks being connected also with one another by the ledge *f* they are prevented from getting easily lost if the plate should break. This connection of the hooks constitutes an important feature of the present invention.

In the modification shown in Figs. 4-6 the ledge *f* is connected with those legs of the hooks *e* which contact with the slate-plate *b*, and the shape of the hooks differs slightly from the shape of the hooks shown in Figs. 1-3, as shown. These hooks (of Figs. 1-3) are illustrated perspectively and on an enlarged scale in Fig. 7 separately, i. e. detached from the slate-plate, but connected with one another by the ledge *f*, and the other hooks (of Figs. 4-6) are also shown separately in Fig. 8, and Fig. 9 shows hooks and ledges of the kind shown in Fig. 7 attached to some slate plates *b* by the intermediary of wooden ledges *d* which are supported by the battens *g*.

I claim:

A slate fastening device, comprising, in combination with the slate plate, a connecting member comprising two coupling members affixed to said plate, and a ledge connecting them with each other, said connecting members being adapted to be attached detachably to a batten from which the said plate is to be suspended, and means located at the ends of the said ledge and connecting it undetachably with the said plate.

In testimony whereof I affix my signature.

CÉLESTIN RIESTERER.
